WELL DRILLING APPARATUS

William J. Newman, Chicago, Ill.

Application March 2, 1931. Serial No. 519,596

9 Claims. (Cl. 255—28)

This invention relates to well drilling particularly as applied to large wells such as used for foundation purposes and which are frequently of from four to six feet in diameter and upwards of 5 one hundred feet or more in depth. In carrying out this invention I supplement the picking and cutting action of suitable excavating devices or drill members, with water and air which serve to agitate the material and tend to prevent the accumulation 10 of excavated material at the bottom of the well. In carrying out these operations I utilize novel drilling apparatus which constitutes the principal features of the invention.

The objects of this invention are to provide an 15 improved drilling apparatus particularly for excavating deep wells which excavation is carried on with the well filled with water or muck; to provide a drilling apparatus with novel means for utilizing water and air under pressure to coact with 20 the drilling members; to provide means for utilizing air for agitating and floating excavated material away from the drill; to provide an improved drill pipe or shaft; and to provide such other improvements and advantages as will appear more 25 fully hereinafter.

In the accompanying drawing illustrating this invention:

Figure 1 is a sectional elevation of a drilling machine for carrying out my improved method, 20 parts being broken away or shown diagrammatically for convenience in illustration;

Figure 2 is an enlarged detail of the swivel head showing the means for supplying water and air to the drill pipe;

Figure 3 is a cross sectional view taken on the line 3—3 of Figure 1;

Figure 4 is an end view of one of the drill pipes taken substantially on the line 4—4 of Figure 1; and

Figure 5 is an enlarged detail of the flange connections between the drill pipes.

As shown in the drawing, 6 represents in general the drilling machine which provides support and power for operating the drilling apparatus, 45 such machine being described in my prior application Serial No. 494,077 filed November 7, 1930. This machine is provided with a driving head 7 which is turned by suitable driving mechanism but as this mechanism forms no specific part of the present invention further description thereof will be omitted. A drill shaft or pipe 8 extends through the head 7 and is turned thereby. This pipe is made up of sections 9 all of which sections serve to coact with the driving head so that the 50 pipe may be extended by merely adding additional

sections as the work proceeds. Each section has oppositely disposed longitudinal projections 10 having grooves 11 therein to provide continuous channels the entire length of the pipe. These grooves are engaged by driving members 12 in the 60 driving head 7, which members may comprise bolts as shown in Figure 3 or other suitable projections which are adapted to slide in the grooves and to turn the pipe. Each section is provided with flanges 13 which are adapted to be connected 65 with the flanges of adjacent sections by means of bolts 14. In order to avoid excessive driving strains on the bolts the flange at the end of one pipe is provided with driving lugs or projections 15 which engage with recesses 16 in the adjacent 70 flange as shown in Figure 5, these lugs and recesses preferably being rectangular in form as shown in Figure 4. When a number of such sections are joined together, it will be seen that the string of pipe thus formed will have a continuous 75 groove or driving slot from the top to the drill head.

The drill or cutterhead 17 is secured to the flange of the lowermost section and is provided with passageways 18 leading to outlet orifices 19 80 adjacent to the cutting members or excavating devices 20. The passageways through the drill head communicate with the hole or passage 21 through the driving pipe or shaft 8.

The pipe 8 is supported by a swivel head 22 85 having an inlet fitting such as a T 23 for the water and air connections. A water hose or pipe 24 is connected with one end of the T and is provided with a check valve 25 of any suitable form which permits water to pass into the pipe 90 but prevents any discharge therefrom. The pipe 24 is connected with a water pump (or other means) for supplying water under pressure, which pressure I have found is effective at about fifty pounds per square inch. An air hose or pipe 26 from any suitable source of air supply 95 adapted to furnish the same under pressure, which pressure I have used at about ninety-five pounds per square inch, is connected with the opposite end of the T 23 and preferably has a branch or extension 27 leading down into the lower branch of the T as shown in Figure 2. The passageway through this branch into the pipe 8 may be somewhat restricted as shown at 28 at 100 the end of the branch 27 so that the air inlet device may act in the nature of an injector to help draw the water in as well as to force it down through the drill pipe.

The swivel head 22 is provided with a bail 110

and is raised and lowered by suitable tackle 30 on the machine 6.

Figure 1 illustrates the apparatus after the well 31 has been drilled a short distance and shows 5 the same full of water, which water carries the excavated material in solution or suspension and is utilized for removing the excavated material from the well, it being understood that water will be more or less constantly forced down through 10 the drill pipe and will overflow at the top of the well thereby carrying off the excavated material. From this it will be seen that as the work progresses, there will be a considerable head of water in the well which tends to resist the discharge 15 of the water forced through the drill pipe and out of the discharge openings 19. However, a sufficient pressure is maintained on the water driven through the pipe so that it will be driven through in considerable volume and will tend to 20 keep the cutting devices clean as well as to remove the excavated or loosened material and force it up with the water out at the top of the well.

While the use of water alone may in some cases 25 be sufficient I have found that it is not entirely satisfactory and therefore utilize the air under higher pressure as an auxiliary means to coat with the water and assist in forcing the water through the drill and connected parts and also 30 to assist in agitating the water and excavated material at the bottom of the well thereby tending to clean the drills and to float or carry up the loosened material. When the air is forced in through the jet or nozzle 27 at sufficiently high 35 pressure, the injector action tends to assist in drawing water through the pipe 24 if water is supplied at the same time and the air and water will be driven downwardly together through the drill pipe 8 and out around the drilling devices 40. The bubbles or streams of air discharged around the drill head are directed toward the cutting area and first tend to force the water against the cutters and then as the bubbles are freed the water is agitated and the bubbles pass 45 up through the water in the well tending to further agitate and float off the excavated material.

In some instances the supply of water through the pipe 24 may be stopped temporarily and the 50 check valve 25 will be closed. Thereupon if air is forced in through the pipe 26 it will drive out the entire volume of water in the drill pipe 8 and connected parts, such water passing with relatively high pressure out through the discharge 55 openings 19. Then as all of the water is driven out from the pipe 8 the air will follow in large quantities further tending to agitate and carry off the material at the bottom of the well.

On account of the relatively large amount of 60 material to be excavated and as such material is frequently heavy clay, hard pan or the like, a large amount of force is necessary to turn the drill head and excessive weight is desirable to expedite the drilling action. For this reason the parts, and particularly the drill pipes, are made 65 heavy so that when the drill is, for instance, ap-

proximately one hundred feet in the ground there is approximately twenty tons weight in the pipe and drill head which is being turned by the machine. On account of such torsional strains I have found it advantageous to provide the co-acting lugs or clutch members on the drill pipes and by having the slots extending through the flanges, a continuous keyway or driving connection is provided so that when the drill has moved downwardly the length of one pipe, the top section may be loosened and another pipe inserted so that the work may progress with but little interruption.

I have found from actual use that apparatus such as described and shown and operated in the manner described will successfully drill through various materials and at satisfactory speeds but it may be desired to change the construction of some of the parts or to operate the same differently under different conditions and therefore I do not wish to limit myself to the forms or operations herein described except as set forth in the following claims in which I claim.

1. A drill pipe having flanges at the ends thereof and having an outwardly facing recess extending the length of the pipe and through the flanges.

2. A drill pipe having longitudinal slots extending the full length thereof for receiving drive members, substantially as described.

3. A drill pipe having longitudinal projections with continuous grooves therein for receiving driving members for turning the pipe.

4. A pipe for actuating a well drill, having flanges at the ends thereof and having longitudinal projections with grooves through the same and through the flanges.

5. The combination with a turning head for well drills having oppositely disposed driving members, of a pipe formed of a plurality of flanged sections with longitudinal grooves therein for receiving said driving members.

6. A string of pipe for the purposes indicated, comprising sections secured together and having a continuous longitudinal slot throughout the length of the string.

7. A drill shaft formed of a plurality of sections which are joined together and which are provided with longitudinal grooves extending throughout the length thereof and arranged in alignment, thereby providing a continuous driving groove throughout the length of the shaft.

8. A drill shaft formed of a plurality of sections, each section having integrally formed flanges provided with interlocking driving means for operatively connecting them to the other sections, said sections having longitudinal grooves which also extend through said flanges.

9. A pipe for actuating a well drill, having an integrally formed flange at the end thereof with driving means adapted to interlock with a similar flange on a coating pipe and having longitudinal projections with grooves through the same and through the flange.
